REFRIGERATING APPARATUS

Benjamin Miller, Chicago, Ill.

Application January 6, 1933. Serial No. 650,404

17 Claims. (Cl. 62—91.5)

The invention relates to refrigerating apparatus and particularly to an automatic temperature control cabinet or refrigerator for cooling ice cream, or other food products, by means of solid carbon dioxide and the vapor therefrom.

One of the important objects of the invention is to provide apparatus which is automatically operated by the melting or vaporization of the solid carbon dioxide which is placed in a movable carrier within a cooling chamber, metallic conductors being provided which assist in the transmission of the cold from the refrigerant carrier to the ice cream or food container.

A further object of the invention is to provide the refrigerant carrier with resilient means, preferably springs, which serve to gradually raise the refrigerant carrier within its chamber as the vaporization of the solid carbon dioxide continues and the solid carbon dioxide diminishes in size.

20 It is a further object of the invention to construct the chamber, within which the refrigerant carrier moves, with two sets of openings or apertures, one set being elongated rectangular openings for the reception of the metallic conductors which contact with the movable refrigerant carrier and the ice cream containers, respectively, and the other set being square, rectangular or round apertures for the passage therethrough of the vapor from the melting or evaporating carbon dioxide to the ice cream or other food product containers.

One of the objects of the invention is to construct the solid carbon dioxide carrier with various means to control the movement thereof and assist in the conduction and passage of the vapor and cold air in the cooling chamber and through the apertures extending through the walls of the carrier chamber.

Another object of the invention is to construct the metallic cold conductors so that they make contact along the length of the ice cream containers and also extend about the top portions thereof to keep the ice cream containers in a constantly cold condition.

It is an additional object of the invention to connect the ice cream containers with cold conducting plates which are independent of the dry ice carrier and chamber.

50 A further object of the invention is to construct the apparatus to form direct passages for the travel of the carbon dioxide vapor and refrigerated air to the ice cream containers.

The invention will be explained and more readily understood when read in conjunction with the 55 accompanying drawings which illustrate one

form of the invention, it being obvious that various changes and modifications in the structure may be made without departing from the spirit of the invention as expressed in the appended claims forming a part hereof.

60

In the drawings:

Figure 1 is a top plan view of the refrigerator showing covers for the ice cream container compartments and the hinged cover of the refrigerant compartment.

65

Figure 2 is a longitudinal cross sectional view of the refrigerator on the line 2—2 of Figure 1.

Figure 3 is a cross sectional view of the refrigerator on the lines 3—3 of Figures 2 and 4.

Figure 4 is a transverse sectional view of the 70 refrigerator on the line 4—4 of Figure 3.

Figure 5 is a front elevational view of the ice cream container showing the metallic cold conductor with its arms embracing the ice cream container and also the cold conducting plates 75 connecting the ice cream containers in the refrigerator.

Figure 6 is a side elevational view of the ice cream container and one of the cold conducting plates and also shows the metallic cold conductor 80 shown in Figure 5.

Figure 7 is a cross sectional view, looking downwardly on the line 7—7 of Figure 2, and illustrates one of the ice cream containers and the metallic cold conductor, and the manner of 85 its fitting in the wall of the cooling chamber.

Figure 8 is a perspective view of the solid carbon dioxide carrier which moves in the cooling chamber which is placed between the ice cream containers, and

80

Figure 9 is a perspective view of the walls of the cooling chamber in which the carrier shown in Figure 8 travels, upwardly and downwardly, portions of the chamber walls being broken away and illustrates the openings in the walls for the 95 reception of the metallic cold conductors and the passage of vapors and cold air.

The refrigerator embodying my invention is constructed with the usual outer metallic wall 10, and the inner curved metallic wall 11, with 100 an intermediate wall 12. Communited cork filling 13 is placed between the walls 10 and 12, and wool or other desirable filling or insulating material is placed between the walls 11 and 12. The bottom wall of the refrigerator is constructed with the floor 15 and the corner boards 16. Communited cork filling material 13 is placed between the floor and the wall 17.

The wall 17 extends from the wall 11 at the outer sides of the refrigerator and supports the 110

lining 18 which forms the floor and side walls of the compartments 19 and 20, which are constructed to receive the ice cream containers 21 and 22, respectively. Only two ice cream containers are shown in the drawings but it will be understood that the refrigerator may be constructed with compartments to contain any desired number of containers and cooling chambers.

- 10 The comminuted cork material extends upwardly into the portion 23 and is covered by the plate 24. The comminuted cork 23 and the plate 24 are placed between the side walls 25 and 26. The side walls 25 and 26 extend upwardly from the walls 17. Metallic cold conductors 27 and 28 are fitted into them and will be further considered hereinafter.

15 The compartment 29 lies between the compartments 19 and 20 which in turn contain the ice cream cans 21 and 22. The inner portions of the curved walls 11 and the walls 25 and 26 confine the insulating wool 14 to the lower portion of the space between the curved walls 11 and the walls 25 and 26, leaving the spaces 30 and 31 for the reception and passage of the vapor from the solid carbon dioxide, as hereinafter set forth.

20 The top of the refrigerator is constructed with the plates 32, the top board 33 and the top covering 34. Tar paper, or other insulating material, 35 is placed between the boards or plates 32. Covers 36 for the compartments 21 and 22, respectively, are provided after the tops of the compartments 19 and 20, have been finished in any well known manner. A hinge cover 37 is fitted into the top of the refrigerant chamber 29. The hinged cover 37 is also provided with comminuted cork 13 which is held in place by the top board 38, side pieces and the retaining plate 39.

25 A lock or catch 40, such as is shown in the drawings, or other suitable means, is employed to keep the cover 37 closed in proper position when the refrigerator is normally in use.

30 The compartment 29 having the side walls 25 and 26 is provided with the end walls 41 and 42. The solid carbon dioxide carrier, generally designated 43, moves upwardly and downwardly within the chamber 29, formed by the walls 25, 26, 41 and 42. The side wall 25 is provided with the vertically extending opening 44 to receive the metallic cold conductor 27, and the side wall 26 is provided with the vertically extending opening 45 to receive the metallic cold conductor 28.

35 The end wall 41 is provided with the opening 46 and the end wall 42 is provided with the opening 47. These openings 46 and 47 may be square, rectangular, round or any desirable form. The walls 25 and 26 are preferably of some material which will assist in the conduction of the cold to the ice cream containers 21 and 22. They may be of pressed wood, or any other suitable insulating material. The end walls 41 and 42 which are shown thicker than the walls 25 and 26, may be of wood.

40 The metallic cold conductors 27 and 28 are each provided with grooves into which the side walls 25 and 26 are fitted. This is best shown in Figures 3 and 7. The metallic cold conductors 27 and 28 are each fitted with the arcuate arms 48 and 49, which embrace and contact the top portions of the curved walls 11 which surround the ice cream containers 21 and 22. The metallic cold conductors 27 and 28 are also provided with the contacting portions 50 and the 45 depending vertical contacting strips 51. The

grooved metallic cold conductors 27 and 28 with their respective arcuate arms 48 and 49, and the contacting portions 50 and depending strips 51 are each preferably integral structures.

50 A large metallic plate 52 connects the curved wall 11 at one side of the ice cream containers and similarly a large metallic plate 53 connects the curved walls 11 at the opposite side.

55 The solid carbon dioxide carrier 43 which travels in the compartment 29 is constructed of metal, to withstand the wear and tear and shock resulting from the frequent dropping of the refrigerant therein and it also acts as a conductor for the cold. The carrier comprises the side walls 54 and 55 and the end walls 56 and 57, and also the bottom 58. There is no top on the refrigerant container or carrier 43. The box or carrier may be reenforced in any desirable way especially at the corners as best shown in Figure 8.

60 The bottom 58 is provided with a plurality of perforations 58a to allow the vapor or gas from the solid carbon dioxide to pass through the perforations into the space beneath the carrier 43 and into the various openings and passages 100 hereinafter described. The walls 56 and 57 are provided with the depending portions 58 and 59, respectively. These dependent end portions or aprons act as cold conductors and also act as closures for the openings 46 and 47 in the 105 end walls 41 and 42. The dependent end portions or aprons extend to a distance short of the ends of the three parallel supporting and cold conducting plates 60. It will be understood that any desirable number of cold conducting plates 110 60 may be used. These supporting plates 60 are in parallel relation and are affixed to the bottom faces of the bottom wall 58. The parallel plates 60 are provided with flanged ends enabling them to be readily secured to the bottom 115 face of the wall 58. When the solid carbon dioxide carrier 43 is in its lowermost position, the lower ends of the plates or supports 60 rest on the top of the wall 24.

65 Four springs 61 have their lower ends secured 120 to the bottom portions of the refrigerant carrier 43 and have their upper ends secured to and suspended from hooks or other supports 62, which are fastened in the walls 25 and 26, respectively or other suitable location in the upper portion 125 of the cooling chamber. These four springs 61 are coil springs and are of the desired strength so that they may serve to operate and control the gradual movement of the refrigerator container upwardly in the compartment 29 during 130 the evaporation of the solid carbon dioxide and thus automatically control the temperature in the cooling chamber 29. It will be understood that other means than the coil springs may be used for the operation of the moving refrigerant 135 carrier. The refrigerant container 43 is caused to descend into the compartment 29 against the action of the coil springs 61 when the solid carbon dioxide is initially placed in the carrier 43.

70 The large metallic plates 52 and 53 which extend from the circular walls 11 in the ice cream container compartments on each side of the compartment 29 are formed with flanged edges so that they form air pockets 63 and 64 extending 145 across the front and back portions of the refrigerator from one freezing compartment to the other in order to hold and trap the carbon dioxide gas and avoid circulation of the gas around the containers.

The operation of the structure of the invention is as follows:

When the solid carbon dioxide of the proper initial weight is placed in the refrigerant container or carrier 43, the solid carbon dioxide causes the carrier 43 to descend in the chamber 29, to its lowermost level as shown in Figures 2 and 4, and the downward progress of the carrier is stopped when the lower edges of the three supporting plates 60 rest on the cooling chamber bottom wall 24. At this time the depending walls or aprons 58 and 59 close the openings 46 and 47 in the end walls 41 and 42. At all times during its movement upwardly and downwardly in the compartment 29, the metallic refrigerant carrier 43 is in direct contact with the metallic cold conductor depending faces 51 of the metallic cold conductors 27 and 28. As the solid carbon dioxide evaporates the refrigerant carrier 43 gradually rises and gradually passes the openings 46 and 47 in the walls 41 and 42, respectively, permitting the vapor from the solid carbon dioxide to pass through the perforations 58a into the space below the refrigerant carrier 43, and to pass through the openings 46 and 47, into the pockets 63 and 64, and the space between the plates 52 and 53 and the outer surfaces of the inner portions of the ice cream can container walls 11 on each side of the cooling chamber 29, thereby also cooling the metallic conductors 27 and 28. The carbon dioxide gas assists the diminishing block of solid carbon dioxide ice in supplying direct cold gas refrigeration.

It will therefore be seen that there is an automatic operation of the cooling system of the refrigerator by the gradual raising of the solid carbon dioxide in its carrier by its evaporation and this evaporation causes the passing off of the carbon dioxide gas through the openings of the cooling chamber to contact with the metallic conductors and the outside portions of the ice cream containers. The refrigerant carrier is gradually raised in the cooling chamber not only by means of the lessening of the solid carbon dioxide but by the action of the four springs.

As the refrigerant carrier is raised with the constantly diminishing solid carbon dioxide, the cooling capacity of the solid carbon dioxide is not lost because the intensely cold vapor seeks the lower levels in the structure and therefore effectively cools the various chambers, passageways and conductors.

The individual metallic cold conductors 27 and 28 with their portions 48, 49, 50 and 51, are constantly in contact with the carbon dioxide gas emanating from the evaporating solid carbon dioxide during the entire raising of the refrigerant cage or carrier, thus conducting cold to the ice cream or other food in the containers.

It will also be seen that the construction of the refrigerator with the various openings and passages which have been described, in which the carbon dioxide gas flows, equalizes the temperature in the refrigerator by means of insulating the bottom portion of the refrigerator so that the carbon dioxide gas cannot reach that portion. To assist in this operation the vertical extensions 51 of the metallic cold conductors are stopped short of the bottom at about the same height as the insulated part in the lower portion of the refrigerator and a little lower than the bottom of the openings 46 and 47, for the passage of the carbon dioxide gas, as indicated at 65 and 66, in Figure 4.

What I claim and desire to secure by letters patent of the United States is:

1. In a refrigerator the combination of a cooling compartment and a movable refrigerant carrier, the refrigerant carrier being suspended in said compartment, an opening in a wall of the compartment, said opening being controlled by the movement of said carrier. 80

2. In a refrigerator the combination of a cooling compartment and a movable refrigerant carrier, the refrigerant carrier being suspended in said compartment, the suspension being effected by resilient means connected with said refrigerant container, an opening in a wall of the compartment, said opening being controlled by the movement of said carrier. 85 90

3. In a refrigerator the combination of a cooling compartment and a movable refrigerant carrier, the refrigerant carrier being suspended in said compartment, the suspension being effected by springs connected with said refrigerant container, an opening in a wall of the compartment, said opening being controlled by the movement of said carrier.

4. In a refrigerator the combination of a compartment, said compartment being adapted to receive food products to be cooled and a cooling compartment, a refrigerant carrier in said cooling compartment, said refrigerant carrier being supported in said cooling compartment by springs secured to said carrier whereby said carrier is adapted to move upwardly or downwardly with or against the action of said springs as the refrigerant in said carrier becomes less, said carrier being independent of the walls of said cooling compartment yet constantly contacting therewith. 100 110

5. In a refrigerator, the combination of a compartment adapted to contain food products and a cooling compartment, a movable refrigerant carrier in said cooling compartment, one wall of said cooling compartment having an opening therein, a cold conductor member in said opening and said refrigerant container contacting with said conductor member in its movement within 115 120 said cooling chamber.

6. In a refrigerator the combination of compartments adapted to contain food products and a cooling compartment, a movable refrigerant carrier in said cooling compartment, two walls 125 of said cooling compartment each having an opening therein, and a cold conductor member in each of said openings, said refrigerant container contacting with said conduction members in its movement within said cooling chamber. 130

7. In a refrigerator the combination of a compartment adapted to contain food products and a cooling compartment, a movable refrigerant carrier in said cooling compartment, one wall of said cooling compartment having an opening 135 therein, a cold conductor member in said opening and said refrigerant container contacting with said conductor member in its movement within said cooling chamber, the refrigerant carrier being suspended in said compartment, the suspension being effected by resilient means connected with said container. 140

8. In a refrigerator the combination of compartments adapted to contain food products and a cooling compartment, a movable refrigerant carrier in said cooling compartment, the walls of said cooling compartment each having an opening therein, and a cold conductor member in each of said openings and said refrigerant container contacting with said conduction members 145

- in its movement within said cooling chamber, the refrigerant carrier being suspended in said compartment, the suspension being affected by resilient means connected with said container.
- 5 9. In a refrigerator the combination of a compartment adapted to contain food products and a cooling chamber, said cooling chamber being formed with walls, each of said walls being provided with an opening, two of said openings being adapted to receive metallic cold conduction members and the remaining two walls each having openings, a carrier for carrying solid carbon dioxide, said carrier being movable within said walls, conduction members in the openings 80
- 10 adapted to receive conduction members, said carrier being in constant contact with said conduction members, and said carrier being supported by springs whereby said carrier may gradually move upwardly as the solid carbon dioxide 85
- 20 evaporates, the vapor from said solid carbon dioxide passing from said carrier into said cooling compartment and through said openings other than the openings adapted to receive the conduction members to cool the food product 90
- 25 contained in said first mentioned compartment.
10. In a refrigerator the combination of a compartment adapted to contain food products and a cooling chamber, said cooling chamber being formed with walls, each of said walls being provided with an opening, two of said openings being adapted to receive metallic cold conduction members and the remaining two walls each having openings, a carrier for carrying solid carbon dioxide, said carrier being movable within said 100
- 30 walls, conduction members in the openings adapted to receive conduction members, said carrier being in constant contact with said conduction members, and said carrier being supported by springs whereby said carrier may gradually move 105
- 35 upwardly as the solid carbon dioxide evaporates, the vapor from said solid carbon dioxide passing from said carrier into said cooling compartment and through said openings other than the openings adapted to receive the conduction members 110
- 40 to cool the food product contained in said first mentioned compartment, walls of said refrigerant carrier being extended to form aprons or closures for said vapor openings.
11. In a refrigerator the combination of a compartment adapted to contain food products and a cooling chamber, said cooling chamber being formed with walls, each of said walls being provided with an opening, two of said openings being adapted to receive metallic cold conduction members and the remaining two walls each having openings, a carrier for carrying solid carbon dioxide, said carrier being movable within said walls, conduction members in the openings adapted to receive conduction members, said carrier being in constant contact with said conduction members, and said carrier being supported by springs whereby said carrier may gradually move upwardly as the solid carbon dioxide evaporates, the vapor from said solid carbon dioxide passing from said carrier into said cooling compartment and through said openings other than the openings adapted to receive the conduction members to cool the food product contained in the first mentioned compartment, walls of said refrigerant carrier being extended to form aprons or closures for said vapor openings, and the refrigerant carrier also being provided with longitudinally spaced plates, the lower ends of which 120
- 70 extend beyond said closures whereby the down- 125
- ward travel of said refrigerant container is limited.
12. In a refrigerator the combination of compartments adapted to contain food products and a cooling compartment, a movable refrigerant carrier in said cooling compartment, two walls of said cooling compartment each having an opening therein, and a metallic cold conductor member in each of said openings, said refrigerant carrier contacting with said conductor members in its movement within said cooling chamber, metallic plates connecting the walls of said food products compartments, said cold conductor members having arms to partially surround the walls of said food products compartments. 130
13. In a refrigerator the combination of compartments adapted to contain food products and a cooling compartment, a movable refrigerant carrier in said cooling compartment, two walls of said cooling compartment each having an opening therein and a metallic cold conductor member in each of said openings, each of said cold conductor members having arms which partially embrace the walls of said food products compartments. 135
14. In a refrigerator the combination of a compartment adapted to contain food products and a cooling chamber, said cooling chamber being provided with openings, said cooling chamber also being provided with a movable refrigerant container, the movement of said refrigerant container controlling the openings and also assisting in controlling the action of the refrigerant. 140
15. In a refrigerator the combination of a compartment adapted to contain food products and a cooling chamber, said cooling chamber being provided with openings, said cooling chamber also being provided with a movable refrigerant carrier, apertures in the bottom wall of the movable refrigerant carrier, the movement of said refrigerant carrier controlling the cooling chamber openings and also assisting in controlling the action of the refrigerant. 145
16. In a refrigerator the combination of a compartment adapted to contain food products and a cooling chamber, said cooling chamber being provided with openings, said cooling chamber also being provided with a movable refrigerant container, the movement of said refrigerant container controlling the openings and also assisting in controlling the action of the refrigerant, said refrigerant container being moved in said cooling compartment by evaporation of the refrigerant and the action of springs. 150
17. In a refrigerator the combination of a compartment adapted to contain food products and a cooling chamber, said cooling chamber being provided with openings, said cooling chamber also being provided with a movable refrigerant container, said refrigerant container also having downwardly extending aprons at its ends and a plurality of longitudinal plates between said aprons, springs attached to the movable refrigerant container, the movement of said refrigerant container and its aprons controlling the openings and also assisting in controlling the action of the refrigerant, said plates between said aprons acting as stops to the travel of said refrigerant container and also as refrigerant conductors, said refrigerant container being moved in said cooling compartment by evaporation of the refrigerant and the action of said springs. 155
